CLAIM

The ornamental design for salad utensil set, as shown and described.

DESCRIPTION

FIG. 1 is a front elevational view of the spoon of my new salad utensil set design;

FIG. 2 is a top plan view thereof;

FIG. 3 is a right side elevational view thereof with the left-side view being a mirror image;

FIG. 4 is a rear elevational view thereof;

FIG. 5 is a bottom plan view thereof;

FIG. 6 is a cross-sectional view along the line 6—6 of FIG. 4.

FIG. 7 is a front elevational view of the fork of my new salad utensil set design;

FIG. 8 is a top plan view thereof;

FIG. 9 is a right-side elevational view thereof with the left-side view being a mirror image;

FIG. 10 is a rear elevational view thereof;

FIG. 11 is a bottom view thereof; and,

FIG. 12 is a cross-sectional view taken along the line 12—12 of FIG. 10.
